VAPOR CONDENSER

John C. Mahoney, Elizabeth, N. J., assignor to
 Alco Products, Incorporated, New York, N. Y.,
 a corporation of Delaware

Application January 25, 1932, Serial No. 588,529

7 Claims. (Cl. 257—223)

My invention relates to vapor condensers and more particularly to a vapor condenser designed to condense hydrocarbon vapors under high pressure.

5 One object of my invention is to provide a vapor condenser which will withstand high pressure.

Another object of my invention is to provide means for eliminating stresses due to differential 10 expansion of the tubes caused by temperature differences existing in the various parts of the condenser.

A further object of my invention is to provide 15 an integral header-forming channel construction capable of withstanding high pressures.

Another object of my invention is to provide a continuous and confined gasket for the header cover enabling the production of a leak-proof joint.

20 Still another object of my invention is to provide an assembly in which the tubes may be readily and easily cleaned and inspected.

A still further object of my invention is to provide a system of baffling which will reduce 25 the fouling of the tubes.

In the accompanying drawings which form part of my specification and which are to be read in connection therewith:

Figure 1 shows a side elevation partly in section 30 of a vapor condenser embodying one mode of carrying out my invention.

Figure 2 is a jogged sectional view taken on the line 2—2 of Figure 1.

Figure 3 is a sectional view taken on the line 35 3—3 of Figure 1.

Figure 4 is a sectional view of the main header.

Figure 5 is a partial sectional view taken on the line 5—5 of Figure 4.

Figure 6 is a detail view showing a section of a 40 modification of the floating header.

Figure 7 is a detail view showing a section of a modification of the floating header.

It is to be understood that like reference 45 numerals in the various views are used to indicate like parts.

In general, my invention consists of a condenser in which the vapors are condensed by the heat exchange with a circulating liquid cooling medium. The condenser is essentially a tube bundle 50 encased in a shell. The vapor to be condensed is circulated around the outside of the tubes. The liquid cooling medium is introduced inside the tubes from a compartment in the header formed by applying a cover to a combined channel and 55 tube sheet member. The tubes are expanded at

one end into the tube sheet which is fixed, and at the other ends, into a plurality of floating or unattached headers. The liquid cooling medium communicates freely between the fixed header and the floating headers flowing through a predetermined course in accordance with suitably located baffles.

More particularly referring now to the drawings, a supporting ring 1 is provided with a plurality of integral lugs 2 which support the condenser. The condenser is shown in the drawings mounted in a vertical position but it is to be understood that it may be mounted horizontally without departing from the spirit of my invention.

The ring 1 is provided with an inlet nozzle 3 for the vapors to be condensed, and an outlet nozzle 4 for the uncondensed portions of the vapors. The peripheral edges of the ring 1 are provided with tongues 5 adapted to cooperate

with suitable grooves in the contiguous members 20 in connection with a gasket to provide sealing means. Secured to the ring 1 by bolts 7 is a channel member 8. The channel member 8 with its cover will hereinafter be referred to as the fixed header. It is an integral member, formed 25

preferably from a single rolled or forged billet. For condensers made in accordance with my invention of somewhat smaller size and design, to withstand less high pressure, the channel member 8 may be a pressure steel casting. Integral 30

with the channel member 8 are a plurality of supporting ribs 9. The ribs 9 are provided with suitable openings 10 to permit the free passage of liquid. The function of the supporting ribs is to give a sturdy construction having a high factor 35

of safety and capable of withstanding high pressure. Baffle plates 11 divide the header into a number of compartments and constrain the flow 40

of the cooling medium through my condenser in a predetermined path. The baffle plates 11 may be machined integral with the channel member 8 or may be formed by separate plates welded thereto. The upper periphery of the channel member 8 is formed with a tongue 12 for cooperation 45

with a groove 13 in the cover member 14. The outer edges of the baffle plates 11 and the supporting ribs 9 are in the same plane as the outer edge of the tongue 12. The cover 14 is provided with grooves 15 and 16 for cooperation with the edges of the baffles and the supporting ribs re- 50

spectively in forming liquid tight joints. The bottoms of the grooves 13, 15, and 16 are in the same plane. Due to the fact that the bottoms of the grooves and the cooperating tongues are in 55

parallel planes, a single continuous gasket 17 may

be inserted between the channel member 8 and the cover 14. The use of a continuous gasket made possible by machining the entire gasket surface in the same plane insures that the gasket 5 stress will be equalized over the entire channel cover. The gasket conforms in shape to the grooves in the cover plate, and it will readily be understood that the gasket is confined by the 10 grooves. This removes the chief cause of unequal tension on the studs. The cover 14 is secured to the channel member 8 by peripheral through bolts 18. Stud bolts 19 are provided for screwing into the supporting ribs 9. The studs may be supplied with cap nuts seated in carefully machined circular grooves upon metal gaskets. 15 Each stud can be individually tightened and kept free from leakage. The studs assist the circumferential bolting in holding down the channel cover against pressure. Vent plugs 20 are provided in the cover 14. The tube sheet is formed by the channel bottom 21'. The tube sheet is made especially heavy in cross section in order to compensate for corrosion and to withstand the high stresses which recent research has demonstrated exists around the tube holes. The tubes 25 21 are made to withstand pressures up to two thousand pounds per square inch and are secured in the tube holes in any approved manner. The channel member 8 is provided with a liquid cooling medium inlet 22 and a cooling medium outlet 23. As pointed out above the channel member 8 and its cover 14 form the fixed header. Extending from the fixed header are the tube bundles having a plurality of independent floating 30 headers at their opposite ends. The floating headers are rectangular in cross section and generally elliptical in shape and are arranged so that the condensate will readily drain therefrom. The floating headers may consist of channel 35 members 24 which are machined out of a single billet as is the case with channel member 8. The channels 24 are provided with covers 25. The channel members 24 are provided with peripheral tongues 26 which cooperate with peripheral grooves 27. A one piece gasket 28 is inserted between the channel member 24 and the cover 25. The covers 25 are provided with suitable vent plugs 26'. The covers 25 are secured to the channel members 24 by means of studs 27'. The number 40 of floating headers may be reduced by employing the floating headers construction shown in Figure 6 in which the channel members 24 are increased in size and provided with an integral supporting rib 28' in the manner of the channel member 8. The cover 25 is secured to the channel member 24 by peripheral studs 27' and stud bolts 29 set into the supporting rib 28.

In the modification shown in Figure 7, the header construction is reversed in that the cover 60 25 forms the tube sheet. The channel member 24 is secured to the cover 25 by studs 27' as before.

Baffle plates 30 are provided between the tube bundles and extend longitudinally to define the 65 vapor path through my condenser. They are designed to permit the shell to be removed. The baffles may be made integral with the shell or may be an assembly clipped to the tube bundles. While I have shown three longitudinal baffle 70 plates, it is to be understood that a single longitudinal baffle or any number of baffles may be used to divide the shell into a suitable number of vapor compartments. The spacing of the baffles from the respective tube sheets will depend 75 upon the volume of the vapor to be handled. It

is to be understood that generally the baffles are placed between the floating headers or, if a single baffle is to be used, it will be placed between the two central headers. The central baffle plate is provided with openings 31 to insure a commingling of the condensate formed in the vapor compartments to permit its withdrawal as a single stream.

In the condensers of the prior art, when applied to certain operations in oil refining, difficulty 10 has been experienced with the formation of deposits upon the tubes in the vapor passage. This is due to the fact that the incoming vapor invariably contains a certain amount of tar or coke, which impinges on the tubes of the condenser.

In my vapor condenser, the vapor enters at the upper section of the first vapor tubes through vapor inlet 3 and flows downwardly along with the condensate formed. The condensate washes 20 down coke and keeps the tubes clean. It is pointed out that this effect is chiefly due to the fact that in the vapor pass the baffle is so arranged that the condensate and the vapor will flow in the same direction.

In the devices of the prior art in which the vapor flows upwardly in the first tubes and the condensate downwardly, the turbulent vapor streams tend to shear away the condensate from the tube walls and expose the bare metal to 30 adhesion of coke or tar.

Shell supporting ring 32 is bolted to the main supporting ring 1 by studs 33. The tongue and grooved joint in connection with the gasket provides a tight joint. The shell is riveted and 35 the shell 34 is riveted to the shell supporting ring 32. A ring 35 is riveted to the lower end of the shell 34. The shell cover 36 is bolted to the shell by bolts 37 and is provided with a nozzle 38 through which the condensate is drained. The 40 shell cover 36 acts as a condensate collector.

In operation, the vapor to be condensed enters my condenser through inlet 3 and passes through the various vapor passes, it having been pointed out that the condensate and the vapors 45 to be condensed pass downwardly in the first vapor pass. The cooling liquid enters first the compartment of the header through inlet 22, passes downwardly to the floating header and upwardly through the tubes 21 to the second compartment of the fixed header, thence downwardly to the next floating header. This route is followed through the subsequent floating headers to the last compartment in the fixed header where the cooling liquid leaves my condenser.

My construction has many advantages. The divided floating headers eliminate danger from excessive temperature stresses which are encountered when a single floating header is used. The separate floating heads divide the total pressure 60 head over a series of separately bolted compartments. Each floating head is free to move as the temperature changes in its particular zone. The use of integral rolled forgings in pressure compartments is a manifest improvement where high 65 pressures are employed. In order to obtain effective rates of heat transfer over a long period, it is necessary to maintain high liquid velocities inside the tubes. Large tube diameters are used in order to reduce the tendency of the cooling 70 medium to form deposits on the inner tube walls. Ordinarily I employ two liquid passes and in no instance do I use more than four liquid passes in a single floating head. The flow is across the short dimension of the floating headers. By using two 75

liquid passes for the head, it is immaterial how much temperature change takes place in one tube bundle inasmuch as the differential expansion will be taken care of by a lateral motion of the head.

5 Due to the fact that the floating heads are suspended freely, the weight of the heads will serve to bring the tubes back into alignment after curvature has occurred due to temperature strains. By supporting the unit from a set of lugs in-

10 integral with the supporting ring which contains the nozzles, it is possible either to drop the shell downwardly or to lift the channel and the tube bundles from the supports for cleaning and inspection. When the shell is dropped downwardly

15 the entire tube bundle is exposed and it is necessary only to remove the bolts on the upper shell joint. Only one liquid connection must be broken, namely the condensate drain line of the shell cover. Corrosion is confined to the shell cover

20 which is removable and replaceable and comparatively inexpensively constructed. The channel which carries the pressure load on the entire unit is located above the shell in contact with dry vapor and out of the range of condensate corrosion.

25 The pressure bearing compartments exposed to corrosion are the floating heads which are made of thick cross section so that the additional metal will be able to withstand corrosive contact. Furthermore, the floating heads are

30 comparatively cheap and may be easily replaced when necessary.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

- 45 1. A vapor condenser comprising in combination a supporting ring, lugs integral therewith and adapted to support the entire weight of the condenser assembly, a header removably secured to one side of said supporting ring and a casing removably secured to the other side of said supporting ring.
- 50 2. A vapor condenser comprising in combination a supporting ring, lugs integral therewith and adapted to support the entire weight of the condenser assembly, a vapor inlet nozzle and a vapor outlet nozzle integral with said ring, a header removably secured to one side of said ring and a casing removably secured to the other side of said ring.

- 55 60 3. A vapor condenser including in combination

a supporting ring, lugs attached to said ring adapted to support the entire weight of the assembly, a fixed header carried by said ring, a plurality of independent floating headers, tubes extending between said headers, said headers being formed by channel members machined out of single billets and cooperating cover plates, and continuous gaskets between said channel members and said cover plates.

4. A vapor condenser having in combination a fixed header, a plurality of tube bundles suspended therefrom, floating headers secured to said tube bundles, said tubes being expanded in respective tubes-holes whereby liquid may flow between the headers through said tubes, said floating headers being supported entirely by said tubes allowing the weight of the floating headers to act in maintaining the alignment of the tubes, a supporting ring, said fixed header attached to and supported by said supporting ring said lugs secured to said supporting ring adapted to support the entire weight of the assembly.

5. In a high pressure hydrocarbon vapor condenser having a supporting ring, a fixed header supported thereby, a plurality of independent floating headers, tube bundles extending between said headers, said floating headers being suspended from said fixed header by said tubes, the combination including a shell surrounding said tube bundles, a plurality of baffles within said shell defining a vapor passage around the tubes, a vapor inlet into said shell, at the upper part thereof, one of said baffles being disposed to effect a downward passage of the incoming vapors, whereby the condensate formed in the first vapor passage will flow downwardly in the same direction as the vapors being condensed to wash the tubes to prevent tar or coke deposits being formed thereon, a removable lower cover for said shell adapted to collect the condensate and a condensate removing nozzle positioned on said cover, and means on said supporting ring for bearing the entire weight of the assembly.

6. A vapor condenser comprising in combination a supporting ring, lugs attached thereto and adapted to support the entire weight of the condenser assembly, a header removably secured to one side of said supporting ring and a casing removably secured to the other side of said supporting ring.

7. A vapor condenser comprising in combination a supporting ring, lugs attached thereto and adapted to support the entire weight of the condenser assembly, a vapor inlet nozzle and a vapor outlet nozzle integral with said ring, a header removably secured to one side of said ring and a casing removably secured to the other side of said ring.

JOHN C. MAHONEY.
